UNITED STATES PATENT OFFICE.

THOMAS J. CONWAY, OF OAKLAND, CALIFORNIA.

MIXING CYLINDER OR DRUM FOR CONCRETE-MIXERS.

1,056,974.

Specification of Letters Patent. Patented Mar. 25, 1913.

Application filed August 5, 1912. Serial No. 713,277.

To all whom it may concern:

Be it known that I, THOMAS J. CONWAY, a citizen of the United States, residing at Oakland, in the county of Alameda and 5 State of California, have invented new and useful Improvements in Mixing Cylinders or Drums for Concrete-Mixers, of which the following is a specification.

This invention relates to cylinders for 10 concrete mixers or like machines, and in particular to that type known as "continuous mixers."

The object of the invention is to divide 15 the body of material passing through the mixer into smaller, separate portions to produce a more thorough mixing of the material than has heretofore been accomplished.

A further object of this invention is generally to improve this class of machinery so 20 as to increase their utility, durability and efficiency.

The invention consists in providing the cylinder proper with a suitable number of spiral tubes, through which the material to 25 be mixed is fed, and in providing means whereby water may be introduced into the tubes at the proper point to give the best results.

It also comprises details of construction 30 which will be more fully explained by reference to the accompanying drawings, in which—

Figure 1 is a side elevation. Fig. 2 is a longitudinal section of the exterior shell 35 showing the tubes in elevation. Fig. 3 is a cross section on line X—X, Fig. 2.

This invention relates to mixing cylinders of concrete mixers and like machines, and in particular to that type known as "continuous mixers."

It consists of a cylinder A of suitable length, which may be mounted or supported in any well-known manner, or, as indicated in Fig. 1 of the drawings, the cylinder may 45 be carried by rollers 2 mounted on a framework 3, and may be revolved at a suitable speed by the gears 4 and 5. The cylinder may also be provided with a feed hopper 6, through which the material is fed to the 50 cylinder, and a discharge chute or hopper 7. Within the cylinder is mounted a suitable number of spiral tubes 8, preferably circular in cross section, as shown in Fig. 3. These are carried and suitably secured at 55 their ends in heads 9 and 10 which entirely close the intervening spaces, as 11, between

the ends of the tubes to prevent the entrance of material into the spaces between the tubes; the heads being designed to entirely close the ends of the cylinder and are only 60 perforated to receive the ends of the spiral tubes 8.

12 indicates a water pipe carried by the cylinder which extends a suitable distance into the cylinder where it is connected by 65 the radial pipes 13 with the spiral tubes 8. The other end of the pipe is connected with a universal union 14, or like device, and is provided with a valve 15 by which the water fed to the spiral tubes is controlled. 70

In operation, the materials to be mixed are dumped into the receiving hopper 6, from whence the mixture enters the spiral tubes 8 when these are in their lower position. By feeding the material through the 75 separate spiral tubes better results are obtained, for the reason that the material is divided into separate, small portions which are constantly being turned and mixed while passing through the spiral tubes. Another 80 advantage which adds to the efficiency of the mixer is the result produced by two different mixing actions which will be described as follows: First, the material is mixed by rolling over and over on itself 85 during the revolution of the cylinder. Second, an end over end mixing action takes place while passing through the spiral tube which is caused by the material constantly rolling down the inclined surface of the 90 spiral tube, as indicated by the arrow a. It can plainly be seen that material picked up by the spiral tubes at the lower portion of the feed hopper will, when carried up to the position shown by the arrow a in Fig. 2, 95 turn over itself and roll down the steep incline of the spiral. This rolling action being in a direction at right angles to the first rolling action described produces an end over end motion of the material. Another 100

advantage gained by the employment of the spiral tubes is that they eliminate the necessity of mounting the cylinder in an inclined position. The material always rolling down the incline of the spiral as the 105 cylinder revolves will insure a positive feed of the material through the tube. The chief advantage gained by mounting the cylinders in a horizontal position is the elimination of thrust bearings and like devices usually employed where the cylinder is mounted in an inclined position. However, when it is 110

desired to produce quicker results, the cylinder may be mounted on an incline, as shown in Fig. 1, which will materially aid in feeding the material through the cylinder. The water may be introduced at any point along the cylinder; the amount being adjusted to a nicely by the valve 15.

While this invention has proven itself particularly adapted for use in concrete mixers, I wish it understood that I do not wish to limit myself to this specific use, as I have found that it has proven very practical and efficient when used for drying purposes, as drying sand in connection with asphalt work. When using it for drying purposes it is only necessary to disconnect the radial pipes 13 and admit steam or hot air through the pipe into the space between the spiral tubes.

Having thus described my invention, what I claim and desire to secure by Letters Patent is—

1. A mixing cylinder comprising a cylinder and a series of spiral tubes within the cylinder, means for conducting material to the spiral tubes, and means for revolving the cylinder.

2. In a concrete mixer, the combination of a cylinder having closed ends and a series of

internal inclosed spiral conductors, said conductors having open ends exposed through the ends of the cylinder, means for revolving the cylinder and means for feeding material to be mixed into said conductors.

3. In a concrete mixer, the combination of a cylinder having heads closing the ends thereof, said ends provided with perforations, a series of independent spirally arranged conductors within the cylinder and having their ends entering the perforations in said heads, means for revolving the cylinder, and means for feeding material to be mixed into the ends of said conductors.

4. In a concrete mixer, a cylinder, a series of spiral tubes within said cylinder, means for feeding the materials to be mixed into the spiral tubes, means for conducting water into the spiral tubes, said means comprising a pipe mounted within the cylinder and connected by radial pipes to the spiral tubes, and means for revolving the cylinder.

In testimony whereof I have hereunto set my hand in the presence of two subscribing witnesses.

THOMAS J. CONWAY.
